(57) **CLAIM**

The ornamental design for a redox flow battery cell stack, as shown and described.

DESCRIPTION

FIG. 1 is a front view of a first embodiment of a redox flow battery cell stack showing our new design;
FIG. 2 is a rear view thereof;
FIG. 3 is a right side view thereof;
FIG. 4 is a left side view thereof;
FIG. 5 is a top plan view thereof;
FIG. 6 is a bottom plan view thereof;
FIG. 7 is a front, top, right side perspective view thereof;
FIG. 8 is a referential top plan view thereof;
FIG. 9 is a cross-sectional view taken along a combination of lines 9A-9B-9C-9D-9E-9F in FIG. 8 thereof;
FIG. 10 is a rear, bottom, left side perspective view thereof;
FIG. 11 is a front view of a second embodiment of a redox flow battery cell stack showing our new design;
FIG. 12 is a rear view thereof;
FIG. 13 is a right side view thereof;
FIG. 14 is a left side view thereof;
FIG. 15 is a top plan view thereof;
FIG. 16 is a bottom plan view thereof;
FIG. 17 is a front, top, right side perspective view thereof;
FIG. 18 is a referential top plan view thereof;
FIG. 19 is a cross-sectional view taken along a combination of lines 19A-19B-19C-19D-19E-19F in FIG. 18 thereof;
FIG. 20 is a rear, bottom, left side perspective view thereof;
FIG. 21 is a front view of a third embodiment of a redox flow battery cell stack showing our new design;
FIG. 22 is a rear view thereof;
FIG. 23 is a right side view thereof;
FIG. 24 is a left side view thereof;
FIG. 25 is a top plan view thereof;
FIG. 26 is a bottom plan view thereof;
FIG. 27 is a front, top, right side perspective view thereof;
FIG. 28 is a referential top plan view thereof;
FIG. 29 is a cross-sectional view taken along a combination of lines 29A-29B-29C-29D-29E-29F in FIG. 28 thereof;
FIG. 30 is a rear, bottom, left side perspective view thereof;
FIG. 31 is a front view of a fourth embodiment of a redox flow battery cell stack showing our new design;
FIG. 32 is a rear view thereof;
FIG. 33 is a right side view thereof;
FIG. 34 is a left side view thereof;
FIG. 35 is a top plan view thereof;
FIG. 36 is a bottom plan view thereof;
FIG. 37 is a front, top, right side perspective view thereof;
FIG. 38 is a referential top plan view thereof;
FIG. 39 is a cross-sectional view taken along a combination of lines 39A-39B-39C-39D-39E-39F in FIG. 38 thereof; and,
FIG. 40 is a rear, bottom, left side perspective view thereof.
